The ornamental design for a cabin for vehicles, as shown and described.

DESCRIPTION

FIG. 1 is a perspective view of our cabin for vehicles according to our new design;

FIG. 2 is a front view thereof;

FIG. 3 is a left-side view thereof;

FIG. 4 is a rear view thereof;

FIG. 5 is a right-side view thereof;

FIG. 6 is a top plan view thereof; and,

FIG. 7 is a bottom plan view thereof.

The design relates to a cabin for vehicles, in particular, military vehicles.

The broken lines showing of portions of the cabin for vehicles are included for the purpose of illustrating environmental structure and form no part of the claimed design.
